UNITED STATES PATENT OFFICE.

LEONARD J. BLADES, OF CHICAGO, ILLINOIS, ASSIGNOR TO NATIONAL TICKET CASE COMPANY, OF CHICAGO, ILLINOIS, A CORPORATION OF ILLINOIS.

COMPARTMENT OR TICKET DRAWER.

1,229,402.

Specification of Letters Patent. Patented June 12, 1917.

Application filed July 17, 1912. Serial No. 709,880.

To all whom it may concern:

Be it known that I, LEONARD J. BLADES, a citizen of the United States, residing at Chicago, in the county of Cook and State 5 of Illinois, have invented certain new and useful Improvements in Compartment or Ticket Drawers, of which the following is a specification.

My invention relates to drawers for cabinets of any kind such as ticket cases and the like which are adapted to contain coupon railway tickets, and the object thereof is to provide a novel and efficient drawer of this character containing several important 15 and advantageous features of construction and having means for properly holding the contents such as tickets, labels and the like within their compartments and for accommodating articles of different lengths.

20 In the drawing Figure 1 is a perspective of my improved drawer; Fig. 2 a cross-section on the line 2—2 of Fig. 1, the same being on an enlarged scale; Fig. 3 a detail sectional view on the line 3—3 of Fig. 1; 25 Fig. 4 a perspective of one of the holders shown in Figs. 1 and 2; Fig. 5 a perspective of a modified form of holder; Fig. 6 a perspective, looking from below, of another modified form of holder; and Fig. 7 a detail 30 view illustrating a modified form of construction of compartments within the drawer.

Referring to the particular embodiment of my invention as illustrated in Figs. 1 to 35 4, a ticket case drawer is here selected for the purposes of a description of my invention although the same is not limited to such particular embodiment. As shown the drawer comprises a frame of suitable material, preferably wood, consisting of two end rails and the two side-rails 2. In order to economize space a series or plurality of these drawers are adapted to slide upon each other and consequently the side-rails have 40 means such as the groove 2^a forming part of the sliding means in connection with a coöperating part on the case or frame (not shown). Each drawer is, in the present instance, provided with a plurality of ticket 45 compartments formed by longitudinal partitions running parallel with the side-rails 2. In order that the partitions may be as narrow as possible, consistent with the required strength and in order to condense the structure, I prefer to make these partitions as

well as the bottom of the compartments of sheet metal which is properly shaped for the purpose. In the particular embodiment of my invention now being described the compartments are formed of a series of longitudinal strips each shaped into channel form thereby providing a bottom portion 3 constituting the bottom of the compartment and the two similar vertical parallel side-walls 4, the adjacent side-walls of two compartments forming a partition. The upper portions of the side-walls 4 are inwardly and downwardly turned and folded against the inner faces of such walls, such infolded portions being indicated at 5. The edges of 60 these infolded portions terminate intermediate the height of the walls 4 thereby forming shoulders 5^a on the inner walls of the compartments and serving the purpose hereinafter explained. These metallic strips are 65 secured to the drawer-frame in suitable manner and in the present instance I have shown the bottom portion 3 of each strip as secured to the under side of the end rails by the fastening devices 6, such as screws or 70 nails and the ends of the partition walls as inserted in and retained by vertical 75 grooves 1^a in the inner faces of the end rails 1.

The compartments above described are 80 adapted to contain the coupon tickets and are preferably of a length to hold the longest ticket of this character in its flat form. In order to designate or mark the 85 contents of the different compartments I 90 secure to the upper surface of the front end rail 1 a metallic strip 7 whose opposite longitudinal edges 7^a are inwardly and downwardly bent in order to form a slide-way for the series of marking or indicating 95 cards 8 on which the proper marking or indication for the tickets may be shown. As illustrated in Fig. 3 this indicating or marking means is located slightly below the top plane of the front end rail, the 100 latter being recessed for this purpose.

Where the tickets are of substantially the same length as the compartments I employ the form of holder indicated at 9 in Figs. 1 and 2, three of these holders being shown 105 in Fig. 1. Each of such holders consists of a metallic strip nearly the same length as the compartments and comprising two right-angled portions, the horizontal portion extending part way over its compartment, 110

thereby keeping the tickets down within the compartment, and a vertical portion which is insertible between and held by two adjacent side-walls 4 of the partition. These 5 holders are thus readily insertible into and removable from any one of the partitions so that they can be moved from one partition to another as may be required. By preference the front edge of the horizontal part 10 of each of these holders is cut away on the bias as indicated at 9^a in order to facilitate the grasping of the front end of the ticket and its removal from the drawer.

However, in many instances the coupon 15 tickets are not of a length to occupy the entire compartment and it frequently happens that some of the compartments contain full-length tickets and others tickets of other lengths. In order to accommodate this variation in ticket lengths it is desirable to provide a ticket holder which may be adjustable for different lengths of ticket, such 20 holder serving to hold down the rear end of the ticket. To this end I provide for 25 each drawer one or more of the adjustable ticket holders indicated in Figs. 1, 2 and 4. These holders are also by preference of 30 sheet metal comprising a bottom portion 10, opposite upwardly extending side flanges 10^a, a vertical end portion or wall 10^b rising from the bottom and a horizontal flange portion 10^c extending partly over the bottom. This holder slides upon the bottom of 35 its compartment and the flanges 10^a are normally outwardly turned or inclined so as to bear against the side-walls of the compartment with sufficient friction to maintain the holder in place and also to 40 engage underneath the shoulders 5^a on the inner opposite faces of the side walls of the compartment whereby the holder is locked in place. The portion 10^c of this form of 45 holder overhangs the tickets within the compartment and keeps them down in place.

45 In Fig. 5 I have shown a modified form of holder comprising the flat horizontal strip 11 and the two opposite flanges 11^a, the latter being arranged to have frictional contact with the side walls 4 of the compartments. In order to limit the adjustment or movement of the holder to a proper position in the rear end of the ticket I provide suitable means which as herein shown 50 consists of the depending fingers 11^b which by preference are made from the same material as the holder itself. It is also desirable to normally lock each of these holders, now being described, within its compartment so that while it is adapted 55 to slide longitudinally out of the compartment it is normally prevented from being removed therefrom or from rising upwardly beyond the top plane of its compartment which might cause interference with the 60 sliding of the ticket drawers one upon the 65

other. To this end I provide each of the flanges 11^a of the holder with one or more projections which are herein shown as tongues 11^c, located at such a height as to engage underneath the shoulders 5^a of the compartments with the result that in the normal operation or manipulation of the holders, the same cannot be removed from their compartments but will yield to application of positive force, particularly when 70 the flanges 11^a are pried away from the side walls 4. It will be understood that the holder is moved forwardly in its compartment so as to cover the rear end of the ticket, which adjustment or movement is 75 limited by the contact of the rear or bottom edge of the ticket with the limiting means 11^b.

In Fig. 6 I have shown another modification of adjustable holder which is adapted 80 to be adjusted to a position intermediate the length of a compartment and adapted to hold in place two sets of tickets in the same compartment, one set being in the forward portion of the compartment and the other set being in the rearward portion 90 thereof. This holder is substantially the same as the holder shown in detail in Fig. 5 but is a double holder, comprising the horizontal portion 12, flange portions 12^a 95 and depending limiting tongues 12^b which project downwardly intermediate the length of the horizontal portion 12, with the result that the rearward end of one set of tickets will extend below the front end of the holder 100 and the front end of the other set of tickets will extend below the rearward end of the holder.

In Fig. 7 I have shown a modified construction of the compartments according to 105 which each compartment is made of a sheet metal strip comprising a bottom portion 13, two opposite vertical portions 14 and a reversely bent portion 15, such latter portion forming a socket in which one of the vertical portions of an adjacent compartment is interlocked. A series of these compartments 110 so constructed and assembled makes practically an integral construction which may be secured to the drawer-frame in the same 115 manner as the construction of compartments before described.

As shown in detail in Fig. 3, I prefer to provide under the strip 7 a dust strip 16 made of felt and the like and secured by the same 120 means as said metal strip 7. The free inner edge of this dust strip which is of double thickness and folded at this edge, extends upwardly in front of and slightly above the corresponding edge of the strip 7, thereby 125 contacting with the drawer immediately above to exclude dust.

As hereinbefore stated, my invention is applicable to drawers generally for whatever purposes used, the embodiment thereof 130

in a ticket drawer being referred to and described above for the sake of a clear understanding of the invention and without intention of limiting myself to such particular use.

5 I claim:

1. The combination of a drawer having a compartment, and a holder slidable therein and comprising a forwardly-extending overhanging strip adapted to hold the articles down within the compartment and side flanges adapted to bear against the side of the compartment.
- 10 2. The combination of a drawer having a compartment provided with shoulders along its sides, and a holder slidable therein and comprising a strip having along the opposite edges of its bottom upwardly-bent side flanges adapted to engage under said shoulders whereby the holder is normally locked against disengagement and adapted to slide within the compartment.

3. The combination of a drawer having a compartment, and a holder slidable therein and comprising a bottom having opposite 25 upturned flanges bearing against opposite walls of said compartment, an end wall rising from said bottom and a flange on the end wall extending over said bottom.

4. The combination of a drawer having a 30 compartment provided with a horizontal shoulder on the inner face of its side walls, and a holder slidable therein and comprising a bottom having opposite upturned and normally outwardly flared flanges bearing 35 against said walls and engaging under said shoulders, an end wall rising from said bottom and a flange thereon extending over said bottom.

LEONARD J. BLADES.
